Patented Sept. 2, 1919.

UNITED STATES PATENT OFFICE.

RALPH R. ROOT, OF CLEVELAND, OHIO.

ELECTRIC SIGNALING DEVICE.

1,314,703.

Specification of Letters Patent. Patented Sept. 2, 1919.

Application filed July 19, 1915. Serial No. 40,543.

To all whom it may concern:

Be it known that I, RALPH R. Root, a citizen of the United States, residing at Cleveland, in the county of Cuyahoga and State of Ohio, have invented a certain new and useful Improvement in Electric Signaling Devices, of which the following is a full, clear, and exact description.

This invention relates to a signaling device of the type known as an electrically actuated vibrator horn.

The object of the invention is to produce a horn of the type in which the parts are largely made of pieces stamped from sheet metal, the pieces being assembled so as to produce a horn in a small number of operations, thereby permitting the horn to be produced at a low cost of manufacture.

Generally speaking, the invention may be said to comprise the elements and the combinations thereof set forth in the accompanying claims.

Reference should be had to the accompanying drawings forming a part of the specification in which Figure 1 is a substantially central sectional elevation of the horn; Fig. 2 is a sectional elevation upon the line 2—2 of Fig. 1; Fig. 3 is a section along the line 3—3 of Fig. 1; Fig. 4 is a section on the line 4—4 of Fig. 1; Fig. 5 is a top plan view of a retaining member used in the horn construction; and Fig. 6 is a side elevation of the part shown in Fig. 5.

The horn shown and described is one in which a diaphragm is vibrated by the movement of an armature of an electro-magnet, the electro-magnet being energized by an alternating current.

At 1 there is shown what I term a base member. This member is formed with an annular offset portion 2 which is adjacent the outer edge. At one portion within the offset part 2 there is an arc-shaped piece of metal 3. This arc-shaped piece of metal is provided with three threaded openings which are adapted to receive the threaded ends of screws 4. The segment portion 3 is of a radius the same as the radius of the circular offset portion 2, and the segment is of such width that it tightly fits into the offset portion 2 at the portion thereof where

it is placed. The metal may be slightly crimped to tightly engage this segment.

The portion of the offset part 2 with which the arc-shaped piece co-operates is provided with three openings which align with the three threaded openings in the arc-shaped piece 3.

A bracket 5 is provided with three openings arranged in the proper position to co-operate with the openings in the offset portion 2 and the arc-shaped piece 3. The screws 4 extend through the openings in the bracket 5 and into the threaded openings in the arc-shaped piece 3, thereby holding the bracket 5 securely to the base 1. The bracket 5 may assume any desired shape, the function being to secure the horn to the support to which it is desired to attach the same.

The base 1 at substantially the central portion thereof is provided with an extending flange 6. This flange at its end portion is inturned, as indicated at 7. The horn proper or amplifier which is indicated at 8, is secured to the flange 6 by having the metal at the inner portion of the amplifier 8 folded or crimped around the flange 7.

By forming the base 1 with its outwardly extending flange 6 and securing the amplifier to this flange, I am enabled to provide a construction such that the air chamber in which the diaphragm operates is not reduced in area at the point where the amplifier is secured to the base. This I believe has a certain effect upon the tone produced by the diaphragm, and the construction has the advantage of preventing any diminution in tone or quality of tone.

At 9 there is indicated a cap or cover member, which with the base 1 incloses the mechanism of the horn, and further provides a support for parts of the horn which will later be described. This casing 9 is of such shape that it may be drawn from a blank of metal, and the outer flange or edge is crimped or bent around the outer flange of the base member 1, as indicated at 10. The cover 9 is provided with an opening 11, the edges of which are bent or drawn outwardly to form a roll. Through this opening 11 the conductors from a source of al-

ternating current may extend to the magnet windings. The roll produced upon the edges of the opening prevents the cutting of the wires by the metal.

5 The diaphragm of the horn is indicated at 12. This diaphragm is preferably a disk of metal of any desired thickness and of any desired kind of metal. The edge or periphery of the disk is held between the cap 9 and 10 the base 1 at the portion where the base 9 is bent round to hold the edge of the base 1. By this construction the diaphragm is securely held at all points to its periphery.

At the central portion of the diaphragm 15 there is an opening through which extends the stud 13. This stud is provided with a reduced portion that extends through the opening of the diaphragm, and the end of the stud is offset upon the inside of the diaphragm, as indicated at 14. This simply holds the stud to the diaphragm. The stud is provided with a central opening which is threaded and receives a screw 15. The stud at the end which is adjacent the amplifier 20 is slotted, as indicated at 16. This slot permits the outer portion of the stud to securely grip the threads of the screw 15 and acts as a lock, for every time the diaphragm moves the tendency of the slotted portion of 25 the stud 13 will be to grip the screw 15 and prevent its rotation.

The head of the screw 15 is toward the amplifier 8 so that a screw driver may be inserted in the head of the amplifier to engage 30 with the screw to turn the screw to any desired position of adjustment.

The core of the electro-magnet is indicated generally at 18. This core is laminated, that is to say, the core is made up of 40 a series of thin plates which when assembled produce the laminated structure. The shape of each of the individual pieces is clearly shown in Fig. 1. When built up the core, therefore, may be described as having a central arm 18^a and side arms 18^b which are joined by a base 18^c. The laminations of the magnet core are held together by means of a retaining strap 19 which is shown in Figs. 5 and 6. This retaining strap is provided 45 with a central offset portion 20, and this central offset portion is provided with a slot 21. The retaining strap has feet 20^a provided with openings by which the retaining member 18 may be held in place.

55 The central arm 18^a of the core extends through the slot 21 of the retaining member 19, the offset portion 20 fitting snugly against the base portion 18^c in the spaces provided between the arms 18^a and 18^b. The 60 offset portion 20 is of slightly greater height than the height of the head 18^c. The retaining member 19 is secured to the cup 9 by means of rivets or other suitable holding devices extending through the openings in the 65 foot 21 of the retaining member 19.

The retaining member 19 in assembling the core is utilized somewhat as a gage, that is to say, the opening 21 is made of a size to receive a definite number of laminated pieces. Therefore, in assembling the horn 70 the central arms 18^a having a sufficient number of laminations are thrust through the opening 21 and when the opening 21 is completely filled the right number of laminations for a core has been taken. The core 75 and the retaining member 19 are then ready to be secured to the cover 9.

The armature for the magnet is indicated at 21. This armature is preferably a circular piece of magnetically permeable material 80 such as soft iron.

This armature is secured to a transverse supporting piece 22. Extending transversely of the armature and the piece 22 is a plate against which the end of screw 15 is 85 adapted to strike. This plate, armature and piece 22 are united or otherwise secured together. This piece 22 is provided with slots 23 adjacent its ends, which slots are adapted to receive the ends of a spring member 24. 90 The spring member is bent somewhat as a yoke and comprises the side pieces 24^a and the connecting piece 24^b. The connecting piece 24^b extends beneath the core 18 and is secured beneath the core and held by the retaining member 19, as heretofore described 95 with respect to the core. From this it will be seen that the retaining member 19 holds all the parts which are carried by the cover 9. The outer ends of the arms 24^a engage in 100 the slots 23 formed in the member 22. The members 24^a are normally under tension, which tends to spread them apart so that when the arms 24^a are engaged and held by the member 22 the arms of the spring member 105 are under considerable tension.

The plate which is carried by the armature engages with the end of the screw 15, and the adjustment of the screw 15 may be varied so as to vary the free swing of the 110 armature 21.

The energizing coil of the electro-magnet is indicated at 26. This coil is wound upon a sleeve 27 which fits over a central portion 115 18^a of the core. This sleeve is split, as indicated at 28, so that the sleeve does not form a complete eddy current. The coils are retained in place with respect to the core of the magnet by turning down the outside laminations so that they form a retaining 120 ledge which engages with the end of the coil, as indicated at 29 in Fig. 4.

The operation of the horn is as follows:

Alternating current is supplied to the coil 125 26. This causes the armature 21 to be alternately attracted and released. As the armature is attracted, the member 22 is caused to bend slightly and slightly flex the arms 24^a of the spring 24. As the armature is released the resiliency of the parts which have 130

- been flexed causes the armature to strike against the screw 15 carried by the diaphragm and so the diaphragm is vibrated. As before stated, the screw 15 may be adjusted so as to vary the free swinging movement of the armature, that is to say, to adjust the free distance between the end of the armature. 70
- It will be seen that in this construction but two rivets are used to fasten the moving parts to the cap or cover, furthermore, that the adjustment is secured from the outside of the horn, thereby making unnecessary the removal of the cap for adjusting purposes. 10
- Furthermore, the edges of the diaphragm are held in a positive and secure manner and are more satisfactory than screws or retaining bolts. 15
- Having thus described my invention, what I claim is:—
1. An electric signaling device comprising a base portion of sheet metal and having a central opening with an upturned flange surrounding said opening, an amplifier of sheet metal, the amplifier being secured to the upturned flange of the base by an interfolding of the metal of the flange and the end of the amplifier whereby the amplifier is secured to the base portion. 20
  2. An electric signaling device, comprising a base portion, an offset or grooved portion in said base, a strip of material within said grooved or offset portion and held therein, said strip of material being provided with threaded openings, there being alined openings in the offset portion of the base, a bracket provided with openings which register with the aforesaid openings, screws extending through the openings in the bracket and engaging the threads in the aforesaid strip, a diaphragm supported from the base, an armature adapted to engage the diaphragm and an electro-magnet for operating the armature. 30
  3. In an electric signaling device, the combination with a diaphragm, an armature adapted to engage the diaphragm, an electro-magnet for operating the armature, a U-shaped spring member having a pair of diverging spring arms with an intermediate connecting portion, a transverse flexible member engaging and retaining said spring arms, the armature being carried upon said transverse member. 50
  4. In an electric signaling device, the combination with a diaphragm, an armature adapted to engage the diaphragm, an electro-magnet for operating the armature, a pair of diverging spring arms, a transverse flexible member engaging and retaining said spring arms, the armature being carried upon said transverse member. 60
  5. In an electric signaling device, the combination with a diaphragm, an armature adapted to engage the diaphragm, an elec- 65
- tro-magnet for operating the armature, a spring member having diverging arms, a transverse flexible member engaging said arms under tension, the armature being carried upon said transverse member. 70
6. In an electric signaling device, the combination with a diaphragm, an armature adapted to engage the diaphragm, an electro-magnet for operating the armature, a spring member having diverging arms, a transverse flexible member engaging said arms under tension, the armature being carried upon said transverse member, and the electro-magnet being mounted between said arms and adjacent the armature. 75
7. In an electric signaling device, the combination with a diaphragm, an armature adapted to engage the diaphragm, an electro-magnet for operating the armature, a pair of diverging spring arms, a transverse flexible member engaging and retaining said spring arms under tension, the armature being carried upon said transverse member, and means for controlling the amplitude of swing of the armature. 80
8. In an electric signaling device, the combination with a diaphragm, an armature adapted to engage the diaphragm, an electro-magnet for operating the armature, a pair of diverging spring arms, a transverse flexible member engaging and retaining said spring arms under tension, the armature being carried upon said transverse member, and regulable means for engaging said transverse flexible member to place the same 90 under initial tension. 95
9. An electric signaling device comprising a diaphragm, an armature adapted to engage the diaphragm to vibrate the same, an electro-magnet, a support therefor, said electro-magnet being made up of laminations, a retaining strap having an opening through which portions of the laminations extend, thereby retaining the laminations in place and securing them to the support. 105
10. An electric signaling device comprising a diaphragm, an armature adapted to engage the diaphragm to vibrate the same, an electro-magnet, a support therefor, said electro-magnet being made up of laminations, a retaining strap having a central portion with an opening therein, said opening being adapted to engage with portions of the laminations to completely hold the laminations with respect to each other, and other portions of the strap being adapted to be secured to a suitable fastening device. 115
11. An electric signaling device, comprising a diaphragm, an armature adapted to engage and vibrate the diaphragm, a laminated core, a support therefor, a spring member having extending arms, a retaining member, said retaining member engaging the parts of the laminated core to hold them together, said spring member extending be- 120
- 125
- 130

neath the core, the retaining member being secured to the support and holding the core and spring to the support, a flexible member supporting the armature, said flexible member being engaged and supported by the arms of the spring.

12. An electric signaling device, comprising a diaphragm, an armature adapted to engage and vibrate the diaphragm, a laminated core having a central projecting portion, a retaining member having an offset central portion with a slot therethrough, the laminations of the central portion of the core extending through the slot in the said 15 retaining member, whereby the laminations

are held together, a support, the said retaining member being secured to the support.

13. An electric signaling device, comprising a diaphragm, an armature adapted to engage and vibrate the diaphragm, and electro-magnet, a spring member extending beneath the core, said spring member having diverging arms, a transverse flexible member which supports the armature, the said 25 transverse member engaging the outer ends of the arms of the spring member.

In testimony whereof, I hereunto affix my signature.

RALPH R. ROOT.
